Primary Examiner — Mark A Goodwin*(74) Attorney, Agent, or Firm* — Masuvalley & Partners(57) **CLAIM**

The ornamental design for an engine hood for work machine, as shown and described.

DESCRIPTION

FIG. 1 is a top left perspective view of an engine hood for work machine showing my new design;

FIG. 2 is a front view thereof;

FIG. 3 is a rear view thereof;

FIG. 4 is a top view thereof;

FIG. 5 is a bottom view thereof; and,

FIG. 6 is a left side view thereof.

The surface shading illustrated in the drawings is provided merely to highlight the contour of design; it is not intended to be illustrative of texture or gloss.

The broken line showing of surface elements and internal hidden in use features is included for the purpose of illustrating portions of an engine hood for work machine and forms no part of the claimed design.
